Des. 968

J. C. Barstow of Providence R. I.
Letters Patent No. 968. Dated Decr. 15th 1857.

The Schedule referred to in these Letters Patent and making part of the same.

Des. 968

To all persons to whom these presents shall come,

Be it known, that I, A. C. Barstow,
of Providence, in the county of Providence and State of Rhode Island, have
produced a new and original design for a laundry stove, and I hereby de-
clare that the said new design is fully described and represented in the fol-
lowing description and accompanying drawings, to which reference is
hereinafter made.

The figures of the accompanying plates of drawings
represent my new design.

In plate 1, fig 1 is an elevation of the front plate.
Fig. 2 is a horizontal section of the same taken in
the plane of the line A. B.

In plate 2, fig. 3 is a plan or top view of the bottom
plate of the stove.

The front plate, fig. 1/plate 1 which is in the shape
of an arc of a circle, has on it two panels aa - aa formed by the raised
mouldings a'a' each ornamented with the raised gothic figures b.b. The
doors c.c. are ornamented with elongated gothic figures b.b.

In plate 2, fig 3. is shown the bottom plate of the
stove having around it the ornamental mouldings d,d, &c. the raised
leaves e,e, &c. f,f &c.

Having thus described my new design, I shall
state my claim as follows,

What I claim as my invention or production, is
the new design for the front and bottom plates of a laundry stove, &c.
consisting of the ornamental configurations as hereinabove described &c. M. P.
and represented in the drawings.
